UNITED STATES PATENT OFFICE.

FREDERICK W. LEONHARD, OF BUFFALO, NEW YORK.

DOOR-LEAF FOR SIDEWALKS, FLOORS, &c.

1,181,779.

Specification of Letters Patent.

Patented May 2, 1916.

Original application filed July 17, 1913, Serial No. 779,501. Patent No. 1,115,554, dated November 3, 1914. Divided and this application filed October 12, 1914. Serial No. 866,240.

To all whom it may concern.

Be it known that I, FREDERICK W. LEONHARD, a citizen of the United States, residing at Buffalo, in the county of Erie and State of New York, have invented new and useful Improvements in Door-Leaves for Sidewalks, Floors, &c., of which the following is a specification.

This invention relates to a panel or door leaf for sidewalks, floors or similar purposes and has the object to provide a door leaf for this purpose which is practically indestructible, to provide such a door leaf having glass vault lights in a reinforced concrete slab and to provide such a door leaf which permits the glass vault lights to be placed directly on and locked to the tensile reinforcement of the concrete slab and give a rough wearing surface.

20 This application is a division of an application on which Patent #1,115,554 was granted to myself, November 3, 1914.

In the accompanying drawings: Figure 1 is a vertical sectional elevation of a panel or door leaf embodying my improvements, taken in line 1—1, Fig. 2. Fig. 2 is a top plan view of the same partly broken away. Fig. 3 is a fragmentary plan view, on an enlarged scale, of a door leaf showing the frame angles and details of vault lights, reinforcement and method of fastening the same. Fig. 4 is a vertical section of the same. Fig. 5 is a vertical section showing the method of tying the minor reinforcement to the major reinforcement.

Similar characters of reference indicate corresponding parts throughout the several views.

In its general construction the panel or door leaf comprises two longitudinal side bars 1, 1, a transverse heel bar 2 connecting the rear ends of the side bars, a transverse toe bar 4 connecting the front ends of the side bars, a longitudinal central bar 5 connected at its front and rear ends with the toe and heel bars, reinforcing wires 9—connecting the bars, bolts 11 and 12 for connecting the reinforcing wires with the bars, a slab 13 of concrete which is supported on the bars and in which said reinforcements are embedded, transparent vault lights 14 of glass or similar material, and metal sockets or receptacles 15 for said vault lights mounted on said reinforcement. The frame bars 1, 2, 4 and 5 may be standard rolled

angles or may be special rolled shapes. The bars 1, 2 and 4 form the four sides of a square or rectangular frame and the vertical legs or flanges of the same provide protection for the edges of the concrete slab or panel 13 while the horizontal legs or flanges thereof provide a seat for the concrete slab 13, also a place for attachment of the reinforcement 9. The central bar 5 is preferably arranged on the center line of the door leaf and connects the heel and toe bars 2, 4. The slab 13 is additionally supported by the reinforcement 9 and some members of the latter are attached to the longitudinal bar 5 thus dividing the rectangular frame 70 into approximately two squares, each of which contains a section of the slab.

The reinforcement for the door slab 13 is composed of steel wire of high tensile strength and is divided into two parts *i. e.* 75 the major 9 and the minor 10 reinforcements. The major reinforcement 9 is made by weaving the wires at right angles to each other. Along two sides of the slab 13 these wires have loops 9^a at one end which engage 80 the head 9^b of a specially designed bolt 11 by means of which they are tied to the door frame bars. On the other two sides of the concrete slab the opposite ends of the wires 9 are stretched around and securely fastened 85 to the adjacent frame bars by other specially designed winch bolts 12 by means of which any slack in these wires may be taken out and certain initial stress given to the same. The advantage of this tying and stretching 90 these wires is five fold. First, it gives a taut rigid mesh in which each wire is doing its full share of work, thus making the slab 13 capable of standing a load at least 10 to 12 times that of a slab reinforced in the 95 ordinary manner or of a slab whose reinforcement is tied but not stretched. Second, the reinforcement is so rigid that it practically takes all the load and whatever beam action there may be, the steel acts immediately instead of allowing an initial deflection to take place in the slab necessary to stretch the slack out of the reinforcement as is the case in ordinary reinforced concrete work. This prevents the concrete from being stretched beyond its elastic limit and cracking of same. Third, it thus becomes only necessary to make the slab 13 of a minimum thickness to afford a good walking surface and provide the necessary stiff- 100 105 110

ness. Fourth, it permits placing the metal cups 15 incasing the glass vault lights 14 directly on the tensile reinforcement and locking them thereto. Fifth, in a reinforced concrete slab of small depth and short span it is hard to develop strength of reinforcement by bond to concrete. Tying and stretching these wires eliminates this difficulty.

- 10 The minor reinforcement consists of steel wires 10 placed adjacent to the vault lights 14 in each alternate rectangular mesh formed by the major reinforcement. They are of such length as will string diagonally across one mesh, wrap once around the junction of the major reinforcement and allow the free ends 10^a to stick up vertically into the concrete. The object of this reinforcement is to give a local support for the concrete and to anchor the concrete securely to the major reinforcement.

15 The special bolt connections are two in number, the first being a tie bolt 11 and the second a winch bolt 12. The tie bolt is similar to an ordinary bolt except that the head 9^b is elongated in the direction of the major reinforcing wire which it engages and is provided at the outer end of the elongation with a depending hook or lug 9^c which receives the loop 9^a on the wire 9 of the major reinforcement. The advantage of this bolt is that it provides a quick and secure tie and keeps the reinforcement at a certain definite distance from the bottom 20 of the slab 13. The nose 9^c of each bolt 9^b is arranged close to or engages with the upper side of the frame so as to confine the loop 9^a of the respective reinforcing wire on its hook and prevent the same from becoming displaced when this wire is put under stress preparatory to embodying the same in concrete. The winch bolt 12 is also similar to an ordinary bolt with a hexagon head except that a vertical groove 12^a is 25 cut in one of its six sides. This groove is of such depth that the upturned part 12^b of the wire 9 which is seated in this groove projects a little beyond the face or side of the bolt head. The object of this groove 30 is best shown by the following explanation as to the method of fastening wire. The bolt 12 is placed in the punched hole of the lower horizontal flange of the respective frame bar with the head on the upper side 35 and the nut 12^c put on but not tightened. The wire of the major reinforcement is placed between the underside of the bolt head and the upper side of the lower horizontal flange of the frame bar and on the 40 side of the bolt shank so that the pull of the wire around the shank of the bolt would tend to tighten the bolt. The wire is then pulled as tight as possible by hand and given a one eighth turn around the shank 45 and then bent up into the groove in the bolt

head, as shown in the upper right hand part of Fig. 3. The wrench is now applied with one jaw gripping the side of the bolt head which contains the groove. This holds the wire securely and the bolt is turned until the wire is tightened the desired amount and then the nut is turned tight. The advantage of this is that it provides for the major reinforcement a quick and secure attachment, taking out all slack and giving a certain initial stress. As the shank of the bolt turns with the wire it thus prevents any local or concentrated stretch of the wire and possible injury therefrom.

50 The slab provides a wearing or walking surface and may be of cement or bituminous concrete or other suitable material. The concrete locks the metal receptacles for the vault lights laterally in place. The glass vault lights 14 are circular in plan and threaded on the circumference, as shown at 14^a, so as to screw into the metal receptacle. They are flat on the top and spherical on the bottom except a small flat shoulder 14^b around the bottom edge which forms a seat 55 for the gasket 16. The extreme edge 14^c of this shoulder is slightly acute so as to grip the gasket. The exterior of the metal receptacles is circular in plan at the upper surface and has an upper octagonal form 60 14^d in the plane of the reinforcement and a lower octagonal form 14^e at the lower surface. These two octagons are not of the same size in plan and are not equilateral but are formed of four alternate long and 65 short sides. The four long sides of the lower octagon 14^e produced would form a square slightly less in size than the square mesh formed by the wires of the major reinforcement. The two octagons are separated by a circular groove, channel or 70 canal 15^a which receives the major reinforcement and this canal forms an inscribed circle in the square formed by the long sides of the lower octagon. The advantage 75 of this construction is that by placing the long sides of the lower octagon parallel with the wires of the major reinforcement the cup 15 drops through the mesh until the lower side of the upper octagon bears on 80 the major reinforcement. The cup is then turned horizontally 45 degrees until the wire reinforcement lies in the circular canal. This forms the vertical lock for the cup or 85 receptacle and the surrounding concrete 90 forms the horizontal lock. The inside of the cup is circular in plan and threaded to receive the thread of the glass vault lights. A clearance is provided between the inside 95 of the cup and the vault light which is 100 filled with suitable cement 15^b to provide for expansion. Around the inside lower edge of the cup there is a shoulder 15^c the 105 edge of which is slightly acute so as to grip the gasket. The vault lights rest on the 110

gasket which forms a tight joint and the gasket is held in place by a metal collar 15^d which in turn is fastened to the underside of the metal cup by tap screws 15^e.

5 I claim as my invention:

1. A door leaf comprising a frame, reinforcing members extending across the space within said frame and consisting of wires, means for attaching said wires to said frame

10 comprising bolts secured to the frame and provided with hooks receiving loops on said wires and each of which has its nose arranged close to the frame for confining the respective loop thereon, and a concrete slab 15 arranged within said frame and receiving said wires.

2. A door leaf comprising a frame, reinforcing members extending across the space within said frame and consisting of wires, 20 means for attaching one end of each wire to said frame, means for tightening said wires comprising bolts mounted on said frame and each adapted to have a part of one wire wound around its shank and provided with a notch in its head which is 25 adapted to receive an upturned portion at

the adjacent end of said wire, and a slab of concrete arranged within said frame and receiving said wires.

3. A door leaf comprising a frame, a reinforcement connected with said frame, a receptacle mounted directly on said reinforcement so as to be supported thereby, a glass light arranged in said receptacle, and a concrete slab arranged within said frame 35 and around said receptacle and receiving said reinforcement.

4. A door leaf comprising a frame, a reinforcement connected with said frame and comprising wires arranged at an angle to 40 one another to form a mesh, a receptacle having grooves on its exterior which receive said wires, a glass light arranged in said receptacle, and a concrete slab arranged in said frame and around said receptacle and 45 receiving said wires.

Witness my hand this 10th day of October, 1914.

FREDERICK W. LEONHARD.
